(57) CLAIM

I claim the ornamental design for an applicator, as shown and described.

DESCRIPTION

FIG. 1 is a perspective top view from above of a first embodiment of the applicator in accordance with the invention;

FIG. 2 is a perspective bottom view from below of the applicator shown in FIG. 1;

FIG. 3 is a plan view of the applicator shown in FIG. 1;

FIG. 4 is a front view to which the rear view, side view and opposite views correspond, of the applicator shown in FIG. 1;

FIG. 5 is a perspective top view from above of a second embodiment of the applicator in accordance with the invention;

FIG. 6 is a perspective bottom view from below of the applicator shown in FIG. 6;

FIG. 7 is a plan view of the applicator shown in FIG. 6; and,

FIG. 8 is a front view, to which the rear view, side view and opposite views correspond, of the applicator shown in FIG. 6.
